UNITED STATES PATENT OFFICE.

ABIJAH R. TEWKESBURY, OF BOSTON, MASSACHUSETTS.

STEERING APPARATUS.

Specification of Letters Patent No. 12,250, dated January 16, 1855.

To all whom it may concern:

Be it known that I, ABIJAH R. TEWKESBURY, of Boston, in the county of Suffolk and State of Massachusetts, have invented 5 a new or Improved Steering Apparatus for Navigable Vessels; and I do hereby declare that the same is fully described and represented in the following specification and the accompanying drawings, letters, figures, 10 and references thereof.

Of the said drawings Figure 1, represents a side elevation of my invention. Fig. 2, is a central and vertical section of it. Fig. 3, is a top view of the case that surrounds 15 the rudder head and is fastened to the deck of the vessel. Fig. 4, is a top view, and Fig. 5, is a side view of the gearing and mechanism attached directly to the rudder head.

In the said drawings, A, denotes the rudder 20 head coming up through the deck B, of a vessel. It is made cylindrical and surrounded concentrically with its axis by a hollow frame or case C, which is firmly fastened down upon the deck. The upper 25 or internal surface of the case C, is provided with a circular ring or flange D, whose two opposite quadrantal arcs are formed on their inner curved surfaces with racks or teeth a, b, while the other two opposite quadrantal 30 arcs c, d, are left without such.

The rudder head has a strong metallic cap E, which is made to inclose it and has four arbors or journals e, e, f, f, extended upwards from its top and near its circumference they being arranged at equal distances apart.

On each of the two arbors e, e, a gear wheel g, and a pinion h, are placed and made to revolve, the gear g, being fastened 40 to the pinion h. Each of the other two arbors f, f, is similarly provided with another such gear g', which is fastened to a roller or wheel i.

While the two pinions h, h, are made to 45 engage respectively with and play into the racks a, b, the peripheries of the rollers i, i, are arranged respectively in contact with the inner surfaces of the quadrantal arcs c, d.

50 All the four gears g, g, g', g', are made to engage with one pinion k, which is arranged between them and fixed on an upright shaft l, that is suitably supported on the rudder head, so as to be capable of being revolved by power applied to it, a hand

or steering wheel I, being fixed at its upper end as seen in the drawings. Directly above the gears, g, g, g', g', and resting on their arbors, there is a circular disk or plate K, which is confined to the several arbors by 60 screw nuts k', k', &c., and screws cut on the arbors, the object of such plate being to keep the arbors and wheel in place or in their normal position with respect to each other.

Over the plate K, and so as to rest on the 65 top of the case C, is a cover I, which simply rests on the case and protects the gearing from rain or dust.

The case C, may be provided with a horizontal slit or opening for the reception of a tiller whenever it may be necessary to use one, the tiller being passed through such and inserted into the rudder head. It is represented in the drawings, although as a general thing it is not to be used in the rudder head when the steering apparatus is in 70 good repair and operation.

75 By rotating the steering wheel the four gears g, g, g', g', are set in motion, and the pinions of two of them work in the stationary curved racks of the case C. They will as a matter of course, produce a rotative movement of the rudder head. In case the rudder should be lifted by a heavy sea, the pinions will be free to rise in the racks and 80 no damage to the machinery will ensue.

85 By means of the rollers i, i, and the curved parts of the ring against which they roll when the rudder is being turned, the correct 90 positions of the teeth of the pinions in the spaced between those of the racks are preserved and so as to prevent inequality of wear on, or injury to the teeth.

The steering apparatus so made and applied to the rudder head is simple, cheap 95 and efficient in its operation and besides it is one not likely to get out of order, while the vessel having it is at sea.

I am aware that mechanism similar in 100 some respects to that employed by me to move the rudder has been applied to capstans. The parts constituting the steering apparatus have never as I believe been arranged and applied to a rudder and the deck of a vessel in the manner which I 105 have above described.

What I claim is—

The arranging the rudder head within a concentric or surrounding frame or case C, fastened to the deck and applying on the 110

top of the rudder head and within the case as described, a driving shaft gearing and one or more curved racks of internal cogs, the whole to be operated by a hand wheel applied to turn the shaft substantially as specified; the said arrangement of parts rendering their combination not only exceedingly efficient and compact as a steering apparatus, but one wherein the lifting or 10 raising of the rudder by a wave or sea is

not liable to injuriously derange the machinery.

In testimony whereof I have hereunto set my signature this eleventh day of May A. D. 1854.

ABIJAH R. TEWKESBURY.
